Application August 6, 1956, Serial No. 602,201

Claims priority, application Great Britain August 22, 1955

8 Claims. (Cl. 123—41.38)

This invention relates to trunk pistons for internal combustion engines and of the kind which comprises a crown from which projects a ring-carrying and skirt portion provided with gudgeon pin bosses, and includes means for retaining a volume of oil in a space between the gudgeon pin bosses and the crown during operation of the piston, which oil is shaken back and forth by the reciprocation of the piston, and is replenished by a jet from a nozzle carried by the connecting rod and directed through an aperture into the space referred to while surplus oil is ejected from the space towards the end of each outstroke of the piston through the same aperture or one or more other passages.

Examples of trunk pistons of the kind referred to are described in the specifications of the present applicant's U. S. Patent No. 2,523,699.

It is an object of the present invention to provide an improved form of trunk piston of the kind referred to which will facilitate manufacture and/or have other advantages.

A trunk piston assembly according to the present invention for an internal combustion engine comprises a piston body including a crown from which projects a ring-carrying and skirt portion provided with gudgeon pin bosses or the like, and a self-contained trough member secured within the piston element so as to be spaced from the crown and lie above the gudgeon pin bosses, which trough member is of annular form and comprises an annular base and inner and outer side walls projecting from the base towards the crown to provide a trough which will retain a quantity of oil, and surrounds an aperture, herein called the central aperture, through which oil can be fed into the space between the trough and the crown from a nozzle on the connecting rod.

For convenience herein it will be assumed that the piston is arranged with its axis vertical and its crown at the top but the invention is applicable to pistons otherwise disposed where, as is usually the case the normal speeds of operation are such that gravity effects can be ignored.

The quantity of oil which, during operation of the piston, will be retained and shaken back and forth in the space between the trough member and the crown depends upon the formation of the piston crown and of the trough member and as will be understood will in any instance be that which provides for the ejection from the space during each complete reciprocation of the piston of just that quantity of oil which is delivered during such reciprocation into the space.

In a piston assembly according to the present invention the arrangement may be such that the ejection of oil from the space takes place substantially wholly through the central aperture, substantially wholly through ejection passages opening at an appropriate level in the trough and extending away from the crown to ejection apertures below the trough, or substantially wholly through one or more apertures between the outer side wall of the trough

2

and the adjacent parts of the piston element or partly in each of two or more of these ways.

In one convenient example of the invention, however, in which the inner surface of the piston crown is domed (i. e. concave) or substantially flat it may be convenient to use an arrangement in which the oil is ejected substantially wholly through the central aperture. In this case it will be seen that the balance between the oil delivered and ejected during each reciprocation of the piston will be reached when the volume of oil lying under the piston crown and immediately above the central opening at the end of each outstroke of the piston equals the volume of oil delivered by the nozzle through the central aperture during each reciprocation. In many cases it may not be desirable or convenient however to give the underside of the piston crown such a shape that the quantity of oil required to be retained for cooling efficiency would be so retained if all the oil lying immediately above the central aperture at the end of each instroke of the piston could be ejected through the central aperture during the succeeding outstroke.

In a piston assembly according to the invention, therefore, the trough member may include or carry a baffle plate lying over part of or the whole of the area of the central aperture and spaced from the inner edge of the trough, so that the required balance between the oil delivered into and ejected from the space between the trough and the piston crown will only be achieved when there is a quantity of oil lying on the side of the baffle plate remote from the crown at the end of each instroke of the piston. The baffle plate therefore is a factor in determining the quantity of oil which will be retained and shaken back and forth in the space between the piston crown and the trough and this quantity can be determined in accordance with requirements by giving to the baffle plate a suitable shape and disposition in relation to the internal shape of the piston element.

Alternatively, and whether such a baffle plate is provided or not, some of the oil may be ejected through a space or spaces between the edge of the outer wall of the trough and the adjacent parts of the piston element, to which and in some cases the outer side wall of the trough may be curved inwards at one or more points, for example over the gudgeon pin bosses, to provide one or more ejection apertures.

Again part or substantially the whole of the ejection of oil may take place through one or more ejection passages each of which opens into the trough for this purpose at a point displaced from the base of the trough and extends to a point within the skirt portion on the side of the trough remote from the crown, the arrangement being such that the volume of oil in the space between the trough and the crown during operation becomes stable when the oil ejected through the ejection passage or passages towards the end of each outstroke of the piston equals the quantity delivered into the space between the trough member and the crown during each complete reciprocation, less any oil which may be ejected through the central aperture and/or between the edge of the outer wall of the trough and the piston body, where the construction is such as to provide for part of the oil to be so ejected.

The trough member will generally conveniently be of oblong or oval form when viewed along the piston axis, with its longer axis extending at right angles to the gudgeon pin axis, and with the central aperture, which is conveniently of slot-like form, extending along that longer axis.

Three constructions according to the invention are illustrated by way of example in the accompanying drawings in which:

Figure 1 is a cross section through one form of piston

according to the invention, the section being taken in a vertical plane containing the piston axis and at right angles to the gudgeon pin axis,

Figure 2 is a cross section of the piston shown in Figure 1 on the line 2—2 of Figure 1,

Figure 3 is a cross section on the line 3—3 of Figure 1,

Figure 4 is a similar view to Figure 1 of an alternative form of piston according to the invention, but with the gudgeon pin and connecting rod omitted,

Figure 5 is a cross section on the line 5—5 of Figure 4,

Figure 6 is a cross section on the line 6—6 of Figure 4,

Figure 7 is a similar view to Figure 3 showing a modification which may be used in some cases,

Figure 8 is a similar view to Figure 4 of a further form of piston according to the invention,

Figure 9 is a cross section on the line 9—9 of Figure 8,

Figure 10 is a cross section on the line 10—10 of Figure 8, and

Figure 10a is a detailed fragmentary cross-section on the line 10a—10a of Figure 10.

In the construction shown in Figures 1, 2 and 3, the piston assembly comprises piston body including a crown 1 from which projects downwards a ring-carrying portion 2 and a skirt portion 3 provided with gudgeon pin bosses 4. When the piston body is assembled in an engine it is connected by a gudgeon pin 5 to a connecting rod 6 containing an oil delivery passage 7 in known manner serving to supply oil to a nozzle 7a from which oil is ejected upwards towards the piston crown at least during the latter part of each upward stroke of the piston.

Secured to a pair of bosses or platforms 8 on the ring-carrying part 2 of the piston body is a self contained trough member of generally rectangular form in plan comprising a base 9 and inner and outer walls 10 and 11, the trough member being secured to the platforms 8 by means of bolts 12 passing through lugs 13 formed on the trough member as shown in Figures 1 and 3. The inner wall 10 of the trough member surrounds a central aperture 14 and has formed integral with it a baffle plate 15 supported from the wall 10 at two opposite sides by webs 16 so as to lie above the aperture 14, as shown clearly in Figure 1. The longer sides of the wall 11 of the trough member lie close to the inner flat faces 4a of the bosses 4 as shown in Figure 3 so that there is only a very narrow space between these longer sides and the faces 4a, while the dimensions of the platforms 8 are such in relation to the dimensions and form of the adjacent shorter sides of the outer wall 11 of the trough member that over a substantial length the upper edges of the shorter sides of the outer wall 11 make a rigid abutment with the platforms 8 as can be seen in Figure 3.

The aperture 14 not only provides the aperture from which oil ejected from the nozzle 7a enters the chamber 1a between the trough member of the piston crown 1 but also substantially the only exit passage for the escape of oil from such chamber.

The dimensions of the baffle 15 are such that it lies substantially completely over the opening 14 so that substantially no oil will be ejected through the aperture 14 at the end of each downstroke of the piston until the quantity of oil in the chamber 1a is such that, when this oil is retained against the underside of the piston crown 1 the lower surface of the oil lies below at least a part of the baffle 15.

During operation equilibrium will be reached approximately when the quantity of oil which lies between the underside of the baffle 15 and immediately over the opening 14 at the end of each upstroke and the beginning of each downstroke of the piston equals the quantity of oil which is delivered from the nozzle 7a into the chamber 1a during each up-piston stroke.

In the modified construction shown in Figures 4, 5 and 6 the construction of the piston body is approximately the same as that shown in Figures 1, 2 and 3 except that instead of gudgeon pin bosses of the form shown in

Figures 1, 2 and 3 having the flat inner faces 4a of substantial area to lie close to the longer outer sides of the trough member, gudgeon pin bosses 17 of approximately circular form are employed and other consequential modifications to the piston body are provided as generally indicated in Figures 4, 5 and 6. In this construction the trough member is of the same general form as that shown in Figures 1, 2 and 3, and corresponding reference numerals have therefore been used for the corresponding parts thereof. In this construction however the baffle 15 lies somewhat nearer to the upper edge of the wall 10 forming the opening 14 and somewhat further from the crown 1 of the piston, and, as will be seen in Figures 5 and 6, the longer sides of the upper wall 11 of the trough are considerably spaced from the adjacent inner surface of the part 2 of the piston. The arrangement is, therefore, such that the trough formed by the base 9 and inner and outer walls 10 and 11 has a volume which is somewhat greater than the volume of the part of the chamber 1a which lies above the dotted line indicated at 18. In operation therefore the oil will build up in the chamber 1a until equilibrium is reached when the volume of oil in the chamber 1a becomes such that at the end of each downstroke of the piston the quantity ejected between the outer edges of the wall 11 of the trough and the inner surfaces of the part 2 of the piston as shown at 18a equals the quantity delivered into the chamber 1a from the nozzle during each upstroke of the piston.

In the modification shown in Figure 7 the piston body 30 would be of approximately the same form as that shown in Figures 1, 2 and 3 with the trough member disposed approximately as shown in Figures 4, 5 and 6 in relation to the piston crown while the form of the trough member is modified as shown at 19 in Figure 7. Thus each of the 35 longer sides of the trough member is of wide angle V form in plan so as to leave substantial spaces 20 between these longer sides and the flat inner faces 4a of the gudgeon pin bosses 4. During operation the ejection of oil to maintain equilibrium will take place between the longer sides 19 of the outer wall of the trough member and the flat surfaces 4a. With the modification shown in Figure 7 therefore the general form of the piston body as regards the gudgeon pin bosses can be the same as that shown in Figures 1, 2 and 3 while the trough member will 40 operate in the manner described with reference to Figures 4, 5 and 6.

In the further modification shown in Figures 8, 9 and 10 the piston assembly is of the same general construction as that shown in Figures 4, 5 and 6 which, will not, therefore, again be described except for a modification to the gudgeon pin boss arrangement which provides for flat inner faces 24 lying close to the longer sides of the outer wall of the trough member as will be clear from Figure 10.

55 In this construction the general dimensions of the trough member, including the height of the baffle member 15 above the upper edge of the inner wall 10 are the same as in Figures 4, 5 and 6 but the trough member is formed in two opposite corners with internal bosses as indicated 60 at 21 the upper faces of which lie below the level of the upper edges of the inner and outer walls, 10 and 11a, of the trough, each of these bosses being hollow and thus providing an exit passage 22 extending to below the bottom 9 of the trough.

65 It will be apparent that in this construction no substantial ejection of oil will take place through the opening 14 unless there is a volume of oil in the chamber 1a great enough substantially to overfill the trough. Equilibrium will be reached when, during the latter part of each downstroke of the piston, the level of the oil thrown into the trough is above the upper faces of the bosses 21 to an extent such that the volume of oil which otherwise would lie above the level of these upper faces approximately equals the volume of oil delivered during each piston upstroke into the chamber 1a. Ejection of oil therefore

takes place substantially completely through the apertures 22 and it will be understood that if desired these may be directed and/or disposed so that the oil so ejected tends not to be ejected on to moving parts of the crankshaft assembly.

One of the advantages of the invention is that it facilitates manufacture since the piston body 1, 2, 3, can be of a form which can be pressed or diecast and the others die-cast and, apart from suitable platform surfaces or the like to which the trough member can be secured, need not have any special internal formation for the retention of oil. Greater freedom for the design of this piston body is, therefore, possible.

It may be possible in many applications in fact to employ a common form of piston body into which a trough member can be assembled when oil cooling of a piston according to the invention is desired or from which the trough member can be omitted and yet a satisfactory piston provided for engines in which oil cooling is not required.

Another advantage of the invention in some instances is that where, as usual and in the constructions shown in the drawings, it is desired to provide a groove for a scraper ring immediately below the grooves for the pressure retaining piston rings, with oil holes immediately below the scraper ring groove as indicated at 23 in Figure 1, the fact that the trough member is self contained enables this to be done without the complications which may arise with pistons as described in the U. S. Patent No. 2,523,699 mentioned above due to the fact that in such pistons the drain holes would be in a position in which oil which may be carried on the inner surface of the piston skirt during the instroke of the piston would by its inertia tend to enter the drain holes during the deceleration and subsequent reverse acceleration of the piston to the position of the integral wall forming the base of the trough and thus prevent draining. Thus with pistons according to the present invention there is no necessity for an integral wall projecting radially inwards from the inner surface of the piston skirt to form the base of a trough, and the drain holes can thus safely enter the interior of the piston at any point below the edge of the outer wall of the trough member.

It will be understood that in piston assemblies according to the invention the trough may be made of the same material as the piston body or of different material. Preferably, however, the trough member and the piston body will be made of materials having substantially the same thermal expansion the piston body and the trough member being formed for example by die-casting.

What I claim as my invention and desire to secure by Letters Patent is:

1. A trunk piston assembly for an internal combustion engine comprising a piston element including a crown, a ring-carrying portion projecting from the crown and a skirt portion integral with the ring-carrying portion and provided with gudgeon pin bosses, and a unitary detachable trough member secured within the piston element so as to be spaced from the crown and lie above the gudgeon pin bosses, which trough member is of annular form and comprises an annular base and inner and outer side walls projecting from the base towards the crown to provide a trough which will retain a quantity of oil and surrounds an aperture, through which oil can be fed into the space between the trough and the crown from a nozzle on the connecting rod.
- 15 2. A trunk piston assembly as claimed in claim 1 in which the self-contained trough member includes a baffle plate lying over at least part of the area of the aperture which is surrounded by the edge of the inner wall of the trough, said plate being spaced from such edge.
- 20 3. A trunk piston assembly as claimed in claim 2 in which the baffle is supported from the edge of the inner wall of the trough member by parts projecting from such inner wall and situated at the opposite sides of the trough which lie adjacent to the gudgeon pin bosses.
- 25 4. A trunk piston assembly as claimed in claim 3 in which the outer side wall of the trough is spaced for part of its length at least from the adjacent parts of the piston element.
- 30 5. A trunk piston assembly as claimed in claim 2 in which the outer side wall is spaced for part of its length at least from the adjacent part of the piston element.
- 35 6. A trunk piston assembly as claimed in claim 1 in which the trough is of generally oblong shape viewed along the axis of the piston, and has a similarly elongated aperture.
- 40 7. A trunk piston assembly as claimed in claim 2 in which at least part of the outer wall of the trough member is spaced from the adjacent part of the piston element.
- 45 8. A trunk piston assembly as claimed in claim 1 in which the trough member has at least one oil discharge aperture the upper end of which opens into the trough at a point below the level of the upper edge of said trough while its lower end opens through the base of the trough.
